LOCK FOR LIQUID DISPENSING DEVICES

George J. Cormier, Fitchburg, Mass.

Application September 8, 1950, Serial No. 183,770

1 Claim. (Cl. 137—383)

1 My present invention relates to a novel and improved lock for liquid dispensing devices, and more particularly to a locking mechanism especially designed for incorporation in a manually operated nozzle unit formed with a valve assembly between the intake and delivery ends thereof to control the flow of fuel therethrough.

In the present day gasoline and oil dispensing, it is customary to pump the liquid into the various tanks or receptacles through nozzle units attached directly to the pump shaft or drum or to a hose connected thereto. Such units are generally in the form of a single casting containing a standard valve construction therein which is conveniently opened and closed by manual pressure applied to a hand lever secured to the valve stem. This has proved to be a most satisfactory arrangement, and particularly efficient from an operator's standpoint, as the flow and stoppage of the fuel may simply and automatically be controlled from the dispensing point.

When the fuel to be dispensed, however, is especially costly, such as oil, gasoline, and the like, it is most important to protect the same from theft or waste by having some practical means to lock the dispensing unit when the same is not in use, and it is the prime object of my invention, therefore, to provide a novel, inexpensive, simple, and efficient mechanism to effect such locking means.

In carrying out my invention, I find that a boss or some similar enlargement may readily be formed on the nozzle or valve casting and appropriately bored at right angles to and interconnecting with the valve stem bore, thus affording an ideal opening for the housing of my novel barrel-type lock constructed with a small lug or element on the inner end thereof, which lug is adapted to project beneath the under surface of a special collar on the valve stem. As thus positioned, the lug is easily rotated by the mere turning of a key in the lock, thereby controlling the vertical position of the valve stem in relation to the valve so that an infallible, positive, and efficient locking arrangement is afforded.

Further objects, features, and details of construction will be hereinafter more fully pointed out in the accompanying description and more clearly defined in the appended claim.

Referring now to the drawings, wherein I show a preferred embodiment of my invention:

Fig. 1 is a cross-sectional view of the valve on an enlarged scale on the line 1—1 of Fig. 2;

Fig. 2 is a front view of the valve;

Fig. 3 is a fragmentary view of the valve stem and valve mechanism; and

2 Fig. 4 is a fragmentary view of the lock and valve stem, in locking position.

In the drawings, I have illustrated my novel invention as incorporated in a preferred type of valve casting, indicated generally at 10, formed of any suitable metal such as bronze, brass, aluminum or the like, and having an intake end 11, appropriately threaded at 12 for attachment to any drum, hose, or fuel supply source and provided with a central opening 14, and a delivery end 15 at substantially right angles thereto and forming a nozzle with a dispensing opening 16. Intermediate said openings 14 and 16 is a valve chamber 17 arranged angularly between the intake 11 and delivery end 15 and formed with a valve seat 18 against which a plastic, fibre, or rubber washer 19 of a valve 20 is adapted to seat.

As clearly shown in Fig. 3, the valve 20 is formed with an upstanding externally threaded and centrally bored stud portion 21, on which said washer 19 is assembled and secured by a locking nut 22, and on its base with a depending nut portion 23, against which one end of an expansible coiled spring 25 is adapted to seat. The lower end of said spring 25 is disposed under compression against the inner face of a removable cap 26, which is suitably threaded for attachment to the threaded portion in the casting 10.

From the outer wall of the casting 10 in opposing alignment to the valve chamber 17 and, hence, angularly in relation to the intake 11 and delivery end 15, I prefer to bore an opening 29 of slightly greater diameter than that of a valve stem 30 adapted to slide freely therethru, and then counterbore a substantially larger opening 32 to slidably hold a collar 31 formed on said stem 30, the bottom of said opening 32 functioning as a stop or seating surface for the collar 31. The valve stem 30 is of appropriate diameter so that the lower end thereof fits loosely into the bored opening in the stud portion 21 of said valve 20, while the upper end 34 thereof is secured in a cooperating recess 35 in a hand lever 36, which handle is pivoted to an upstanding ear 37 on the casing 10 at 38.

45 To provide an effective housing for my lock, I prefer to form a boss 40 on the casting 10 having a central bore 42 as indicated in dotted lines, Fig. 2, extending into said opening 32 at right angles thereto and of suitable diameter to receive the inner reduced portion 43 of a barrel lock 44, which may be readily swaged or otherwise secured in the counterbore 41, also shown in dotted lines, Fig. 2, drilled in the outer portion of said boss 40.

50 As a locking element adapted to project for-

wardly from the end of the portion 43 and beyond the outer marginal edge of the shoulder 31, I have provided a small lug 45 which is rotatable by a key 46 turned in the lock 44, thus controlling the vertical movement of the valve stem 30.

In locked position, the lug 45 will be positioned as shown in heavy lines in Fig. 4 and will retain the valve stem 30 and collar 31 as shown in Fig. 1; whereas by turning the key, the lug will rotate to a position shown in dotted lines at 45 in Fig. 4, which of course will permit the opening of the valve 20 by downward pressure exerted on the handle 36. If desired, I may elect to drive a small pin 47, or the like, thru the casting 10 and into the opening 42 to provide a stop 48 to limit the lateral motion of the lug 45 and, thus, prevent complete rotation of the same.

In utilizing my novel unit, the intake end 11 is threaded into a correspondingly threaded fixture on any desired fuel source, thereby permitting the liquid to flow through the opening 14 into the valve chamber 17 where it is checked by the valve 20, and held tightly closed against the valve seat 18 by the action of the spring 25. The valve 20 will remain closed until downward pressure is exerted thereon by the valve stem 36, thus opening the valve 20 and permitting the liquid to pass into the delivery end opening 16 and thence into the receptacle to be filled. Such downward pressure is readily applied by the action on the stem 30 of the handle 36 connected at one end thereof.

As thus arranged, a satisfactory fuel dispenser is presented but with no provision against theft or leakage if the same is left unattended.

And inasmuch as the slightest pressure on the handle 36 will cause the valve 20 to open, it is important to have a positive locking means to prevent movement of the valve stem 30 in the direction of the valve 20; and it is equally important to have a locking mechanism which will in no way interfere with the dispensing of the fuel when the same is being effected.

From the foregoing, it will be appreciated that I have devised such an efficient locking construction and one that is mechanically simple and inexpensive to produce. As shown, I prefer to employ a barrel lock 44 disposed in the unit at right angles to the valve stem 30, said lock being formed with a lug 45 on the inner end thereof which is adapted to be moved into locking or unlocking position by the turning of the key 46 in the lock 44. To cooperate with the lug 45, I provide the collar 31 on the valve stem 30 and counterbore the recess 32 for the collar to freely slide in. When the operator desires to lock the unit, he merely turns the key in a clockwise direction until the lug 45 strikes the stop 47, thus automatically projecting the lug 45 to a position beneath the marginal edge of the collar 31 and creating a positive lock against any downward pressure on the handle 36.

Conversely, when the operator desires to restore the unit to operative condition, he merely

turns the key in a counter-clockwise direction until the lug 45 strikes the stop 47, thus automatically removing the lug 45 out of contact with the collar 31. Thereupon said collar may be forced to slide downwardly against the tension of the spring 25 until it seats at the base of the counterbore 32 by downward pressure on the handle 36, thereby causing the valve 20 to open and the liquid to flow freely therethrough, as long as the handle 36 is held downwardly.

While I have shown and described one embodiment of my invention, I do not wish to be limited thereby as it is apparent that my locking construction may be applied to divers uses without departing from the spirit of the invention as defined in the appended claim.

I claim:

A liquid dispensing fitting of the kind described, comprising a casting having a hollow intake portion and a hollow delivery nozzle portion substantially at right angles to each other, and a valve chamber positioned intermediate said portions with an opening into each portion, a valve seat and a valve in said chamber to arrest flow to the delivery nozzle, a coiled spring fitting in said intermediate valve chamber and normally holding the valve on its seat, said casting being formed with an opening through the wall of the delivery nozzle and an enlarged cylindrical recess at the outer surface in alignment with said opening and the intermediate chamber, a stem attached to the valve opposite said spring and slidably extending through said opening and carrying a cylindrical collar adapted to closely slide in said enlarged recess, a boss formed on the outer surface of said casting adjacent said enlarged recess and fitted with a pivoted handle extending in alignment with the outer end of said stem and engaging the same, said casting having a lateral lock-receiving opening from the exterior into said enlarged recess, a barrel lock fitted within said opening and carrying a lug projecting from its inner end and into the enlarged recess under said collar and engaging the collar in a locking position when the valve is closed, partial rotation of said barrel lock acting to withdraw the lug from locking position and permitting the collar to closely slide in said enlarged recess and to open said valve against the tension of the coiled spring by pressure on the pivoted handle.

GEORGE J. CORMIER.
